Patented Dec. 3, 1968

212,852

TOPIARY SHAPE OR THE LIKE

Herman Silverman, Doylestown, Pa. 18901

Filed Oct. 6, 1965, Ser. No. 87,349

Term of patent 14 years

(Cl. D29—1)

FIG. 1

FIG. 3

FIG. 2

The stand portion, disclosed in broken lines in the figures, is included for illustrative purposes only.

I claim:

The ornamental design for a topiary shape or the like, as shown and described.
